A. LEFKOWITZ

PYJAMA PANTS

Filed July 15, 1925

UNITED STATES PATENT OFFICE.

AMELIA LEFKOWITZ, OF NEW YORK, N. Y.

PYJAMA PANTS.

Application filed July 15, 1925. Serial No. 43,690.

My invention relates to pyjama pants, my more particular purpose being to make the garment of such construction as to adapt it for a number of different uses and to increase its serviceability as well as its appearance.

Reference is made to the accompanying drawing forming a part of my specification, and, in which like reference characters indicate like parts throughout each of the figures.

Figure 1 is a fragmentary front elevation showing my improved pyjama pants as they appear when worn ordinarily and as closed in the front.

Figure 2 is a fragmentary front elevation showing the pants as they appear with the front open, the slit being concealed by the flap.

20 The body member of the pants is shown at 3 and the legs at 4 and 5.

The body member is provided at its upper edge with a waistband 6, having the general form of a tubular hem, and extending 25 through this waistband is a belt 7. The belt may be made of any suitable material such as cloth or leather, and preferably has the form of a flat and strong tape. The belt can be tied into a knot 8, or fastened in any 30 equivalent manner well known in this art.

The body member 3 is provided with a pair of mating portions 9 and 10, which are movable relatively to each other, and may be drawn apart as indicated in Figure 2.

35 The waistband 6 extends along the top of these portions. The portions 9 and 10 can be drawn angularly apart as indicated in Figure 2, by merely sliding the adjacent portions of the waistband 6 along the belt 7.

40 The portions 9 and 10 are provided with buttons 11 and 12, each spaced a little distance away from the adjacent outer or free edge of the portion upon which it is secured.

The body member 3 is further provided 45 with a flap 13 secured firmly to it, and provided with button holes 14 and 15 which match the buttons 11 and 12.

The flap may be raised into the position indicated in Figure 1 and held in that position by the buttons. Again, the flap may be lowered, in which event it simply hangs down.

Whenever the flap is raised into the position indicated in Figure 1 and buttoned as shown in that figure, the portions 9 and 10 can be moved apart, within limits permitted

by the buttons 11 and 12, which hold these parts relatively to the flap 13.

That is to say, when the flap is buttoned up as indicated in Figure 1, the operator can shift the flaps 9 and 10 slightly to promote the comfort of the wearer, but can not displace these flaps to any great extent because they are held from undue displacement by the buttons 11 and 12.

When, however, the flap is unbuttoned and lowered, the portions 9 and 10 of the garment may be moved apart freely; the Shirring of the waistband 6 readily permitting this movement, and the buttons 11 and 12 being free to move further apart because no longer confined by the flap.

A pair of pyjama pants made in accordance with my invention may be worn around the house with comparative freedom if 75 brought into the condition indicated in Figure 1. Thus at all times and particularly during hot weather, the wearer of the pants may without impropriety have considerable freedom of movement in walking 80 around the house and in this way my garment promotes comfort and convenience, without any offsetting drawbacks. As may be readily understood from the foregoing description, the body member of the pants 85 is provided at its front with a slit, and at its top edge with a shirred waistband, the latter being open in front and provided with end portions which extend substantially to the slit, these end portions being slidable 90 upon the belt 7 and thus movable toward and from each other as guided by the belt, in order to shift the adjacent portion of the body member so as to close and open the slit. It will also be noted that the flap 13 95 is wide enough to cover the slit whether open or closed, and is free to swing into different normal positions relatively to said body member, in order to cover and uncover the slit.

The fastenings whereby the flap is held in position to cover and thus conceal the slit are located far enough apart to enable the flap to extend entirely across the slit whether open or closed. In other words the buttons 11, 12, with their respective button holes are spaced apart by practically the full width of the flap, this width being adequate to enable the flap to conceal the slit, even when opened to its maximum limit.

Thus it is practicable for the wearer to either open or close the slit, as his comfort

may require, without disturbing the flap from its position indicated in Figures 1 and 2.

I do not limit myself to the precise construction shown, as variations may be made therein without departing from my invention, the scope of which is commensurate with my claim.

Having thus described my invention, what I claim as new and desire to secure by Letters Patent is as follows:

In pyjama pants, a body member provided at its front with a slit, and at its top edge with a Shirred waistband open in front and with its end portions extending substantially to the slit, the end portions of the

waistband being movable toward and from each other in order to shift the adjacent portions of said body member and thus to close and open said slit, said adjacent portions of 20 said body member being free and adapted to meet together so as to completely close said slit throughout its entire length, a flap connected with said body member and wide enough to cover said slit whether open or 25 closed, said flap being free to swing into different normal positions relatively to said body member in order to cover and uncover said slit, and means for securing said flap in position to cover said slit and thereby 30 conceal the same.

AMELIA LEFKOWITZ.
